US00D469593S

(12) United States Design Patent (10) Patent No.: US D469,593 S
Funk et al. (45) Date of Patent:  Feb. 4, 2003

(54) CEREAL BAR HAVING A CEREAL PIECE INCLUDED THEREON

(75) Inventors: Dean F Funk, Brooklyn Park, MN (US); Dena K Strehlow, Maple Grove, MN (US)

(73) Assignee: General Mills, Inc., Minneapolis, MN (US)

() Term: 14 Years

(21) Appl. No.: 29/111,592

(22) Filed: Sep. 30, 1999

(51) LOC (7) Cl. 01-01

(52) U.S. Cl. D1/101

(58) Field of Search D1/125-128, 129, D1/199, 100, 101; 426/18, 89, 104, 19, 549, 559, 560, 618-622, 439, 449, 450, 281, 282, 452, 453, 458
